M. J. Gordon INVENTOR
BY *G. H. Gray* ATTORNEY

UNITED STATES PATENT OFFICE.

MILTON J. GORDON, OF WEEHAWKEN, NEW JERSEY.

DESIGN FOR AN EMBROIDERED ART PANEL, BANNER, OR FLAG.

54,909.

Specification for Design.

Patented Apr. 20, 1920.

Application filed March 22, 1918. Serial No. 224,081. Term of patent 3½ years.

To all whom it may concern:

Be it known that I, MILTON J. GORDON, a citizen of the United States, residing in Weehawken, Hudson county, and State of New Jersey, have invented a new, original, and ornamental Design for Embroidered Art Panels, Banners, or Flags, of which the following is a specification, reference being had to the accompanying drawing, forming part thereof.

The figure of the drawing is a plan view

of an embroidered art panel, banner or flag substantially illustrating my new design.

I claim as my invention:

The ornamental design for an embroidered art panel, banner, or flag substantially as shown.

Signed at town of Weehawken, county of Hudson, and State of New Jersey, this 20th day of March, 1918.

MILTON J. GORDON.
